STEER HEAD FOR PLAYGROUND EQUIPMENT

Ronald W. Zick, Minneapolis, Minn., assignor to
The Toro Company, Minneapolis, Minn.

Filed Feb. 10, 1975, Ser. No. 548,554

Term of patent 14 years

Int. Cl. D21—03

U.S. Cl. D34—5 L

FIG. 3

FIG. 1

FIG. 2

FIG. 4

FIG. 5

FIG. 1 is a front elevational view of a steer head for playground equipment embodying my new design;

FIG. 2 is a right side elevational view thereof, the left side view being a mirror image;

FIG. 3 is a top plan view thereof;

FIG. 4 is a bottom plan view thereof; and

FIG. 5 is a rear elevational view thereof on a reduced scale.

I claim:

The ornamental design for a steer head for playground equipment, as shown and described.
